UNITED STATES PATENT OFFICE.

GEORGE N. JEPSON, OF WORCESTER, MASSACHUSETTS.

CALCINING-FURNACE.

No. 806,894.

Specification of Letters Patent.

Patented Dec. 12, 1905.

Application filed February 25, 1903. Serial No. 144,983.

To all whom it may concern:

Be it known that I, GEORGE N. JEPSON, a citizen of the United States of America, and a resident of the city and county of Worcester, 5 Commonwealth of Massachusetts, have invented certain new and useful Improvements in Calcining-Furnaces, of which the following is a specification.

My invention relates to a calcining or roasting furnace in which certain ores are subjected to continued high temperature for the purpose of driving off the water of combination.

My invention is not confined to any particular kind of ore; but it may be used with good 15 effect in calcining bauxite. Some bauxite ores contain about thirty per cent. of water of combination, which can only be driven off at red heat. Not only is it necessary to subject the ore to a high temperature, but to continue the heat for a considerable time, for 20 while the larger percentage of moisture is driven off in a comparatively short time or at a lower heat the last traces disappear only after the ore has been heated to a high heat 25 for a considerable time. It will be noted, therefore, that for economical operation the calcining-furnace must be constructed to hold the heat and to allow all parts of the mass of ore to be subjected directly to it. Other 30 considerations are freedom from constant manipulation of the ore, continuous operation, ease of charging and discharging, avoidance of waste by escape of dust, the protection of the ore from direct contact with the products of 35 combustion, and others which will appear in the description which follows.

My invention consists in a furnace the chamber of which contains a number of refractory tubes open at each end and into which the raw 40 ore is charged and from which it is drawn after calcining. These tubes are preferably vertical, the ore being charged at the top and discharged at the bottom by gravity.

The furnace is preferably of the downdraft 45 type, the burning gases being introduced near the top of the chamber and the products of combustion being carried off in flues at the bottom to a chimney.

In order to fully understand my invention, 50 reference is had to the accompanying drawings, in which—

Figure 1 shows a longitudinal section of the furnace taken through the chamber and fire-boxes and showing the refractory tubes in elevation. Fig. 2 is a transverse section, and 55 Fig. 3 is a horizontal section.

The bottom 10 of the chamber A is suitably supported over the discharging or receiving chamber B. Said bottom consists of the hearth 11 and the perforated floor 12, between which 60 the flues 13 are located. Said hearth is of fire-brick supported on cast-iron plates 14, which are mounted on I-beams 15, the ends of which are embedded in and supported by the walls 16 17. 65

The heating-chamber A is formed by the walls 18, 19, 20, and 21 and the arched top 22. The inside of the chamber is lined with fire-brick, as shown at 23. The fire-boxes 24 25 are located in end walls 18 and 19, respectively, and consist of the usual grate 26 26', fire-door 27 27', and ash-pit 28 28'. The flues 30 31 are made between the end walls 18 19 of the chamber and the walls 16 17, extended upward to direct the burning gases upward toward the upper part of the chamber. The chamber contains the vertical refractory tubes 32, which are supported on the hearth 11 and extend loosely through the collars 33 in the top 22, allowing the vertical expansion and contraction of said tubes through the top. These tubes are open at the bottom through suitable openings in said hearth and the plates 14 and communicate with the spouts 34. They may be closed by slidable fire-brick doors, as 85 35, which are operated in the slides 36 by suitable rods and handles 37. The tops of said tubes are closed by covers 38. The flues 13 in the bottom 10 communicate with the chimney 40 through the flues 13'. 90

The operation of the apparatus is as follows: Fires are laid in the fire-boxes 24 25, and the burning gases coming therefrom are directed through the flue 31 up into the top of the chamber A. There they beat against the tubes 95 32 on their way downward to the flues 13 13', passing then to the chimney. By suitable regulation of the size of the openings to the flues in the floor 12 the heat is held in the chamber until the refractory walls of the fire-brick tubes 32 have absorbed it and until the heat is practically constant throughout the said chamber. A red heat is thus constantly maintained in the walls of the tubes. The ore is then charged into the tops of the tubes, 100 the gates 35 being closed, and the covers 38 are replaced. The ore is thus subjected to the high heat of the inside surface of the tubes. No manipulation of the ore is necessary, as 105 the heat held by the fire-brick tubes acts directly on the ore to the center of each tube. The moisture appears to be absorbed by the 110

highly-heated surface of the fire-brick, and complete calcination takes place in a comparatively short time. The ore is not subjected to the direct action of the flame, and thus any 5 impurities from the products of combustion do not become mixed with the ore, and fine ore and dust which might be carried off up the chimney if subjected to the direct action of the flame are saved. After the calcination 10 is completed the gates 35 are drawn and the ore discharged into the chamber B, where it can be taken up as needed. A new charge can then be introduced as before, and thus the furnace run continuously, or small charges 15 can be introduced more frequently and a portion of the contents of each tube drawn to make the operation more continuous.

My invention is not confined to driving off the water from bauxite or other ores, but may 20 be used for roasting ore to expel arsenic or sulfur or for other purposes for which it is necessary to heat ores.

I claim—

1. A downdraft calcining-furnace comprising a heating-chamber, a fire-box, flues connecting the fire-box with the upper portion of 25 said chamber and flues at the lower portion of said chamber for carrying away the products of combustion, a series of tubes within said 30 chamber and extending through the walls thereof, and collars fitted within the walls of said chamber and loosely surrounding said tubes whereby the tubes are permitted to expand longitudinally.

2. A downdraft calcining-furnace comprising a heating-chamber, a fire-box, flues connecting the fire-box with the upper portion of 35 said chamber and flues at the lower portion of said chamber for carrying away the products of combustion, a perforated floor interposed 40 between said heating-chamber and said lower series of flues for retarding the exit of the heated gases, a series of tubes within said chamber and extending through the walls thereof, and collars fitted within the walls of 45 said chamber and loosely surrounding said tubes whereby the tubes are permitted to expand longitudinally.

3. A downdraft calcining-furnace comprising a heating-chamber, a fire-box, flues connecting the fire-box with the upper portion of 50 said chamber and flues at the lower portion of said chamber for carrying away the products of combustion, a perforated floor interposed between said chamber and said lower series 55 of flues, a series of flues extending through the walls of said chamber and through the perforated floor and collars loosely surrounding the said tubes and placed within the walls of the furnace to allow of longitudinal expansion of said tubes.

Signed by me at Worcester, Massachusetts, this 21st day of February, 1903.

GEORGE N. JEPSON.
